UNITED STATES PATENT OFFICE.

EUGENE S. LOVETT AND SIDNEY T. ALDRICH, OF LOWELL, MASSACHUSETTS.

AUTOMATIC TRAIN-STOP FOR RAILWAYS.

1,201,320.

Specification of Letters Patent.

Patented Oct. 17, 1916.

Application filed June 4, 1914. Serial No. 843,079.

To all whom it may concern:

Be it known that we, EUGENE S. LOVETT and SIDNEY T. ALDRICH, both citizens of the United States, residing at Lowell, in

5 the county of Middlesex and Commonwealth of Massachusetts, have invented jointly a certain new and useful Improvement in Automatic Train-Stops for Railways, of which the following is a specification.

10 This invention relates to automatic train stops for railways where the train is provided with air-brakes, and has for its principal objects: Means for operating the valve of the supplementary reservoir to release the 15 air from said reservoir to the atmosphere; means comprising a supplementary air-chamber, or reservoir, for collecting and removing condensed moisture from the compressed air thereby preventing the brake 20 from being rendered inoperative by freezing; improved means for raising the trip-rod out of operative position from the cab of the engine; and convenient means for returning trip-rod to operative position.

25 This train-stop may be operated by any movable piece, as the draw of a draw-bridge, a switch or a semaphore, which is in a position to make the passing of a train dangerous or impossible and which is suitably connected to an actuating trip.

In the accompanying drawing Figure 1 is a right side elevation of so much of a locomotive engine provided with our improvement as is necessary to the understanding 35 of the same; Fig. 2, a right side elevation of the train-stop with the trip and track rails, the parts being about to be operated; Fig. 3, a right side elevation of the train stop being operated; Fig. 4, a plan of a part of 40 the bent lever, connecting rod and valve-operating or trip-lever; Fig. 5, a horizontal section of the valve slide, supplementary reservoir and hanger, on the line 5 5 in Fig. 2, the valve being closed; Fig. 6, a vertical 45 section of the same on the line 6 6 in Fig. 3, the valve being open; Figs. 7 and 8, respectively, a side elevation and a front elevation 50 of the trip-box and trip in operative position; Fig. 9, an isometric view of the trip located between the rails of a railway track, a semaphore in indicating position and the connecting means between the semaphore and the trip.

In Fig. 1, A denotes the boiler; a a^1 the 55 driving wheels, $a^2 a^3$, the truck wheels; a^4 , the breast-beam; a^5 , the pilot, B, the back

of the cab; b the floor of the same; these parts of a locomotive engine being of any usual construction. C C¹ are the rails of the track.

60 The usual main reservoir auxiliary air-chambers or reservoirs and train-pipe are applied in substantially the customary manner to the locomotive and cars.

The hanger D of the valve-case may be 65 secured to any convenient relatively stationary part of the engine but is here represented as supported by an angle-iron or bracket d (Figs. 1 and 5) bolted to the breast-beam a^4 . The valve-case E is represented as an externally-threaded hollow cylinder which is screwed into an internally threaded hole in the hanger D. The valve 70 e^1 is represented as a frustum of a cone and has a stem e^2 which runs in guides $e^4 e^5$, 75 secured to the front and back of the case E.

A spring, represented as a spiral spring e^6 , surrounding the valve stem e^2 and compressed between the valve e^1 and the guide e^4 , tends to push said valve from its seat. 80 A slide F is movable horizontally in ways f^1 , integral with or secured to the outer or front face d^1 of the hanger D and is provided with a stud f^2 which projects from said outer face and with a double incline f^3 , 85 the middle portion of which normally bears upon the outer end of the valve stem e^2 and holds said valve to its seat, the valve being opened by the spring e^6 when said incline is moved horizontally in either direction 90 off from said stem. The incline f^3 has a groove f^4 , which is square in cross-section, to receive the end e^7 of the valve stem e^2 , which is also square in cross-section, to prevent the valve from turning and to cause 95 it to seat the same at all times.

The supplementary reservoir G is integral with or secured to the inner or rear face of the hanger D and surrounds in an airtight manner the rear end of the valve-case. 100 and is provided with a coupling nipple g to which the train-pipe is connected in practice.

The trip-lever H is provided with a longitudinal slot h which allows said lever to 105 move longitudinally and to turn upon the fulcrum h^1 and upon the stud h^2 , a stop-pin h^2 passing transversely through said slot limiting the downward movement of said lever. When said trip-rod or lever H is 110 turned on the fulcrum h^1 in either direction far enough, it moves the slide F and causes

the incline f^3 to slide off from the valve-stem, allowing the valve to be opened by the spring e^6 or by the pressure of the air in the supplementary reservoir G, and the air to escape from said reservoir into the atmosphere, as through openings f^4 f^5 in said slide F.

The upper end of the trip-lever H is connected by a link i to the front end of an arm i^1 fast on a rock-shaft I, journaled at i^2 on the frame a^6 of the engine, another arm i^3 fast on said rock-shaft being jointed to the front end of a rod j which reaches into the cab and is jointed to a lever J which being drawn backward will raise the link i and trip-lever into a vertical position in such a manner as to force the slide F to its normal position and close the valve. By means of the lever J the engineer can raise the trip-lever high enough to clear the trip K, hereinafter described.

The upper end of the link i is very loosely connected to the arm i^1 , to allow the upper end of the trip-lever H to move with great freedom, by means of a pin i^4 which passes through the forked front end of said arm i^1 and through a large triangular hole i^5 in the upper end of said link, which hole i^5 permits sufficient movement of said trip-lever without any movement of the arm i^1 , but when said arm i^1 is raised the rod j will let go after being drawn as above described, will be returned to normal position by a spring, represented as a spiral spring j^1 surrounding said rod j and compressed between a collar j^2 fast on said rod, and the back of the cab.

A trip K (Figs. 7, 8 and 9) is pivoted at k to move in a plane at right angles to the track-rails C C¹ and is represented as arranged within a box k^1 secured to a base plate k^2 on the cross ties L L and provided with a hinged cover k^3 which is struck and raised by swinging said trip from its horizontal inoperative position to a vertical position when said trip projects above the top of the box and above the cover. When the trip is being restored to inoperative position, it strikes a hook k^4 jointed to the underside of the cover and draws the cover down, closing the box and excluding rain, snow and dirt.

The trip K is represented as connected below its pivot k by link k^5 and rod k^6 to a lever k^7 which is connected by rods k^8 k^9 to another lever k^{10} , the last named lever k^{10} being connected by a rod to one arm of a bell-crank lever k^{11} , the other arm of which is

connected by the rod M to the blade n of a semaphore N, so that raising said blade 60 raises the trip into operative position and lowering said blade returns said trip to inoperative position. Obviously, the lever k^{10} might turn upon a vertical as well as upon a horizontal pivot and rod M might connect 65 said lever to any movable part used in or about a railway to raise the trip by moving said part to a certain position.

One of the rods b^8 and the arms of the levers k^7 k^9 connected by said rod may be 70 dispensed with.

The most convenient position for the trip-lever and trip will be midway between the rails of the track to accommodate trains 75 passing in either direction.

We claim as our invention:

1. The combination of a valve, automatic means for opening said valve, a slide having an incline normally to close said valve, a normally vertical trip-lever to operate said slide to release said valve, a rod arranged to slide longitudinally and to be operated from the cab of an engine, a rock-shaft having an arm jointed to said rod and having another arm provided with a pin and a link, one end 80 of which is pivoted to the upper end of said trip-lever and the other end of which is provided with a triangular slot loosely to receive said pin, to enable said trip-lever to be restored to normal position by drawing 85 said rod.

2. The combination of a valve, automatic means for opening said valve, a slide having an incline normally to operate said slide, to release said valve, a rod to close said valve, a normally vertical trip lever arranged to slide longitudinally and to be operated from the cab of an engine, a rock-shaft having an arm jointed to said rod and having another arm provided with a pin, a link one end of 90 which is pivoted to the upper end of said trip-lever and the other end of which is provided with a triangular slot to loosely receive said pin to enable said trip-lever to be restored to normal position by drawing said 95 rod, and a spring to return said rod to normal position.

In witness whereof we have hereunto affixed our signatures in presence of two witnesses.

EUGENE S. LOVETT.
SIDNEY T. ALDRICH.
